SAFETY WINDOW CHAIR

Frederick R. Zabel and Robert Penner,
New York, N. Y.

Application February 17, 1934, Serial No. 711,630

9 Claims. (Cl. 304—27)

The present invention is concerned with a safety window chair.

It is the primary object of the invention to provide a collapsible chair adapted to be conveniently set up and mounted on a window sill so as to overhang the outside wall of a building to sustain a person and permit the latter to comfortably clean the outside surface of a window.

It is a particular object of the invention to provide a novel window chair having a seat removably mounted on a window sill to overhang an outside wall of a building which cooperates with means carried by the chair to resist sagging of the seat.

It is a further object of the invention to provide a readily operable but collapsible and rugged safety window chair which will stand up under considerable usage and which when disorganized or out of adjustment may be readily repaired or adjusted by the removal and replacement of relatively few inexpensive parts.

It is a further object of the invention to provide a collapsible chair having swingable and slidable sides adapted to be rectilinearly retracted upon rearward displacement of the back wall of the chair.

It is a further object of the invention to provide a collapsible chair having a seat and cooperating swingable sides adapted to removably sustain a swingable back of the chair against said seat.

It is a further object of the invention to provide a collapsible chair including swingable castings adjustably and slidably carrying arcuate bracing members.

It is a further object of the invention to provide a collapsible chair adapted to cooperate with an elongated bar disconnectably supported on a window sill on the inside of the building whereby clamping instrumentalities associated with said bar serve to hold and prevent lateral displacement of the chair.

It is a further object of the invention to provide a safety window chair which may be conveniently collapsed as to occupy a relatively small space.

Other objects, advantages, and features of the invention are in part obvious and in part herein-after pointed out.

For a clearer understanding of the invention attention is directed to the embodiment shown in the accompanying drawings in which:

Fig. 1 illustrates a side elevation of the safety window chair, according to the invention, shown mounted on a window sill and overhanging an outer wall of a building.

Fig. 2 is a plan view of Fig. 1.

Fig. 3 is a section on the line 3—3 of Fig. 1 on a larger scale.

Fig. 4 is a fragmentary view of Fig. 1 on a larger scale.

Fig. 5 is a rear view of Fig. 1.

Fig. 6 is a section on the line 6—6 of Fig. 4 and

Fig. 7 is a plan view of the safety window chair shown collapsed or folded.

The safety window chair is generally designated 10 and comprises a relatively wide and flat seat or base 11. As shown the seat is substantially square in configuration but the invention is not limited in this respect. If desired, of course, the seat may be of any suitable configuration.

The seat is provided with spaced upstanding flanges 12 and 13 which are interconnected by a common rear upstanding flange 14. According to the invention seat 11 together with the spaced side flanges 12 and 13 and the rear flange 14 are formed or stamped out of a single piece of sheet material, preferably of an appropriate metal. Flanges 12, 13 and 14 constitute therefore, an integral three sided rim extending above the elevation of the base plate or seat 11.

Straddling each of the spaced side flanges and appropriately secured thereto is a pair of spaced brackets as 15 and 16, each of which define hollow ears or curved guiding members as 17 to slidably and rotatably receive displaceable rod 18 bodily carried by the coiled ears 19 and 20 depending from the swingable and foldable spaced side wings 21 which may be slidably displaced longitudinally of and relative to an associated side flange of the seat. The coils 15, 16, 19 and 20 in association with its rod 18 in fact constitute a hinge connection permitting a side wing 21 to be swung towards or away from the seat 11. It will be noted that a strap as 22 is secured to each side wing 21 and has its lower portion coiled about the intermediate guide ear 20 to reinforce the latter.

The upper face of each side wing is preferably beaded as 23 to present a relatively smooth contour, and each bead operatively includes a suitable spring actuated plunger 24 adapted to removably interlock with a recessed plate 25 carried by the rear flange 14, that is to say, when a side wing is swung towards the seat 11, plunger 24 will automatically lock and hold the side wing in a closed or folded position.

A rod 26 extending across the width of seat 11 and slightly spaced therefrom has its ends appropriately secured to the spaced side flanges 12 and 13. The swingable back wall 27 has a re-

flexed end 28' movably coiled about the fulcrum rod 26 providing a hinge connection therewith to permit back 27 to be swingably moved towards and against seat 11 or away therefrom.

5 Extending rearwardly from the back wall 27 is a pair of flanges or ribs as 28 each adapted to be removably received in a groove or channel 29 formed by a terminal and inwardly turned flange 30 associated with each side wing 21. In setting 10 up the chair, the side wings are first raised from the back wall 27 after which the back wall is raised from the seat permitting spaced ribs 28 partly interlocked with the inturned flanges 30. As the back wall 27 is progressively swung rearwardly ribs 28 will be fully and completely received by the inturned flanges. In the progressive and gradual reception of the ribs 28 as the 15 back is moved rearwardly, side wings 21 are rectilinearly displaced rearwardly. Consequently, it may be advisedly stated that the rear wall 27 constitutes actuating means for interlocking ribs 28 with the cooperating receiving channels 29 of the side wings for the dual purpose of holding the back and side wings assembled and for preventing the collapse or folding of the rear wall 27 and side wings, it being noted that ribs 28 of the rear wall are of a less width than the height of the side flanges as 13 (see Fig. 4), hence permitting the back wall 27 and its ribs 28 to be confined within the three sided rim formed by the side flanges 12 and 13 and the companion rear interconnecting flange 14.

25 In folding or collapsing the safety chair, the back 27 is first disconnected from the side wings and swung to lie against the seat 11. Side wings 21 are then moved rectilinearly and forwardly on their respective side flanges and subsequently swung inwardly until spring actuated plunger 24 interlocks with a companion holding plate 25.

30 It is thus apparent that the side wings 21 hold the back wall 27 against its seat. In unfolding the chair, from its collapsed form, plunger 24, may be readily disconnected from the holding plate 25 by applying an upwardly directed finger pressure on beaded edges 23, the back wall 27 being also provided with a beaded edge 31 to present a relatively smooth contour as is well understood.

35 Suitably attached to each of the rear corners on the lower face of the base plate or seat 11 is a bracket 32 each having spaced coiled bearings or eyelets 33 and 34 depending therefrom. A pin or rod 35 is appropriately sustained and journalled in each of the bearings 33 and 34. Hingedly and swingably mounted between bearings 33 and 34 40 and carried by rod 35 is an arcuately coiled flange 36 extending upwardly from an inner plate 37 of a swingable casing generally denoted 38 which comprises suitably interconnected spaced plates as 37 between which is adjustably and slidably 45 guided an arcuate shaped brace or leg 39, the lower terminal of which carries a removable rubber socket 40.

50 Interposed and suitably attached between a pair of plates 37 of each hinged casing is a pair of spaced anti-friction rollers 41 on which an uninterrupted face 42 of brace 39 is slidably mounted. Each casing 38 also is provided, an appropriate guide block 43 interposed and sustained between plates 37. Hence each brace 39 55 is slidably guided between a stationary guide block 43 and companion spaced anti-friction rollers 41.

55 A bell crank lever or latch dog 44 is pivotally carried between the spaced plates of each hinged casing and cooperates with spaced notches 45

whereby a leg or brace 39 may be adjustably set relative to a respective casing. A projection as 46 carried at the upper ends of each brace 39 overhangs one of the spaced plates and prevents accidental withdrawal of a brace from its casing in the event latch dog 44 has been accidentally displaced out of a notch 45. Cooperating with latch dog 44 is a relatively flat spring 47 which serves to positively hold the former in a desired notch. The tension of spring 47 may be adjusted by a set 10 screw as 48.

Since the casings 37 are hinged they may be swung towards or away from the bottom face of seat 11. In their folded or collapsed position they are substantially parallel to the bottom face of the 15 seat and approximately in alignment as indicated in Fig. 7. The casings are held locked in their folded position by reason of a spring actuated plunger 49 operatively held in a depending bracket 50 attached to the lower face of seat 11, that is to 20 say, plunger 49 removably interlocks with the spaced sides 37 of an associated casing 38 to prevent the latter from swinging away from the seat of the safety chair.

25 With the casings 37 swung to the vertical positions that is, substantially perpendicular to seat 11 as indicated in Fig. 5, they are sustained and locked in such position by the cooperating snap lock complements, namely a lug or spheroidal shaped member 52 extending from eyelet 36, which member is adapted to be removably held by an interlocking lip or socket 53 carried by a resilient hollow strap 54 attached to side flange as 13. It is thus apparent, that the casings 37, when in their folded position are prevented from 35 swinging away from seat 11 and when in operative position for supporting the seat, they are prevented from being accidentally folded towards the seat.

30 Having unfolded and locked the several parts of 40 the safety window chair in their desired positions, the chair may be placed out of a window and mounted on a sill thereof so as to overhang an outside face of a building for sustaining an operator desiring to work on the window or the outside 45 part of the building. To this end, a relatively flat retaining bar 54 is first mounted on the window sill 55 of frame 56. This bar extends across the entire width of the window frame 56, with the ends of the bar abutting the sides of 50 the frame. The channelled end 57 of the seat 11 is then moved rearwardly so as to receive the flat retaining bar 54. Channel 57 is formed by first bending the forward end of the seat 11 downwardly and subsequently folding a portion of the 55 downwardly bent end rearwardly as to be substantially parallel to the body of the seat.

35 With the seat interlocked with the flat retaining bar 54, spaced collars 58 which encompass the bar 54 are then slidably moved against the 60 side flanges 12 and 13 and clamped to the bar by the wing clamping nuts 59 to prevent lateral displacement of seat 11. In Fig. 1 it will be noted that the seat is interlocked with the retaining bar 54 and has its rearward portion overhanging the 65 front wall 60 of a building. In such position braces 39 have their resilient or rubber sockets abutting the building. These braces also resist the load applied on the seat, preventing the latter from sagging. In a seated position, the operator 70 may easily clean a window as 61.

40 To remove the chair from the window, side clamp collars 58 are released. Subsequently, seat 11 is disconnected from the interlocking retaining bar 54. The chair is then free to be 75

bodily moved through the window and inside of the building. The chair may be folded or collapsed. Back wall 27 is moved downwardly and the side wings 21 are swung towards the back wall 27. Following this, casings 38 are swung inwardly, hence causing the arcuate braces to overlap in flatwise relationship and these are held against each other and the innermost thereof against the seat by reason of the snap lock plunger 49. In this collapsed form, the chair occupies a relatively small space and may be easily and conveniently transferred from place to place by utilizing the handle 62 mounted on the rear flange 14.

15 While the invention has been described in detail and reference has been made to specific applications thereof, it is to be understood that the invention herein disclosed is not limited to such specific applications and it is intended that all matter contained in the above description or shown in the accompanying drawings shall be interpreted as illustrative and not in a limiting sense.

We claim:

25 1. In a device of the class described, retaining means removably mounted across a window frame of a building, a seat removably interlocking with said retaining means and in part overhanging an outside face of said building, spaced casings 30 hinged to said seat, means for locking said casings when disposed substantially perpendicular to the bottom face of said seat, an adjustable arcuate brace slidably carried by each casing, means to lock each brace in an adjusted position, and separate means to prevent displacement of said casings when disposed substantially in horizontal alignment.

40 2. In a device of the class described, retaining means removably mounted across a window frame of a building, a seat having one end removably interlocking with said retaining means and another end overhanging an outside face of said building, spaced members hinged to said seat, an arcuate brace bodily and adjustably carried by each member, each member having a complementary locking portion, means depending from the sides of said seat adapted to removably interlock with a complementary locking portion of an associated member, each brace having a resilient socket adapted to abut an outside face 45 of said building, said braces preventing sagging of the overhanging part of said seat, and means to prevent removal of a brace from an associated member.

50 3. In a window chair, retaining means, a seat having a channeled portion removably interlocking with said retaining means and another portion adapted to overhang an outside face of a building, swingable and settable means carried by said seat to prevent sagging of said overhanging portion, means for holding said swingable and settable means adjacent said seat, said chair having hinged and spaced side wings, and a swingable rear wall, said rear wall having means 55 cooperating with corresponding terminals of said wings to displace the latter rearwardly upon swinging of said rear wall rearwardly.

70 4. In a safety window chair, the combination of, retaining means, a seat having a channeled portion removably interlocking with said retaining means and another portion adapted to overhang an outside face of a building, swingable and settable means carried by said seat to prevent sagging of said overhanging portion, locking 75 means for holding said settable and adjustable

means flatwise adjacent said seat, said chair comprising side wings having terminal channel portions, and a swingable rear wall hinged to said seat having means cooperating with said channel portions to rectilinearly displace said wings and removably interlock therewith.

5 5. In a collapsible safety window chair, the combination of, a relatively elongated bar, a seat having a channel portion removably interlocking with said bar and another portion adapted to overhang an outside face of a building, adjustable and settable means carried by said seat to prevent sagging of said overhanging portion, locking means for holding said settable and adjustable means flatwise adjacent said seat, said chair comprising rectilinearly displaceable hinged and spaced side wings having terminal channelled portions, a swingable rear wall hinged to said seat and having rearwardly disposed flanges adapted to be received by said channelled portions to rearwardly displace said side wings.

10 6. In a collapsible safety window chair, the combination of, a relatively elongated bar, a seat having a channeled portion removably interlocking with said bar and another portion adapted to overhang an outside face of a building, swingable spaced members hinged to said seat, brace means adjustably and slidably sustained by said members, means to prevent displacement of said brace means relative to said members when the latter are disposed substantially perpendicular to said seat and separate lock means to prevent displacement of said members when the latter 15 are disposed substantially parallel to said seat.

25 7. In a collapsible safety window chair, the combination of, a relatively elongated bar, a seat having a channeled portion removably interlocking with said bar and another portion adapted to overhang an outside face of a building, adjustable clamping means slidably carried by said bar to prevent lateral displacement of said seat, swingable spaced members hinged to said seat, arcuate and notched brace means adjustably and slidably sustained by said members, means to prevent displacement of said brace means relative to said members when disposed substantially perpendicular to said seat and means to prevent displacement of said members 30 when disposed substantially parallel to said seat.

40 8. In a collapsible safety window chair, the combination of, a seat having hingedly connected sides, and a hinged rear wall, said wall and sides having cooperative means to rearwardly displace said sides upon rearward displacement of said rear wall.

45 9. In a collapsible safety window chair, the combination of, a seat comprising a channel portion, adjustable and swingable braces having corresponding portions adapted to be bodily moved towards the center of and adjacent said seat, disconnectible complementary locking means to prevent displacement of said braces, said chair having rectilinearly displaceable spaced hinged 50 side wings and an independently hinged rear wall, the latter being adapted to be swung against said seat and said side wings against said rear wall, disconnectible complementary locking means to prevent displacement of said side wings 55 relative to said rear wall, said seat having a handle for bodily carrying said chair from place to place.
